TETHERED BALL GAME APPARATUS

Robert C. Wilson, Chula Vista, Calif.

Application September 7, 1954, Serial No. 32,184

Term of patent 14 years

(Cl. D34—15)

Figure 1 is a side elevational view of a tethered ball game apparatus, showing my new design;

Figure 2 is an end elevational view thereof; and

Figure 3 is a top plan view thereof.

I claim:

The ornamental design for a tethered ball game apparatus, as shown.
